UNITED STATES PATENT OFFICE.

MOSES E. PIERSON, OF EMPORIUM, PENNSYLVANIA, ASSIGNOR TO NOVELTY INCANDESCENT LAMP COMPANY, OF EMPORIUM, PENNSYLVANIA, A CORPORATION OF PENNSYLVANIA.

INCANDESCENT-LAMP-STEM-SEALING MACHINE.

1,004,071.

Specification of Letters Patent. Patented Sept. 26, 1911.

Application filed December 14, 1909. Serial No. 533,047.

To all whom it may concern.

Be it known that I, MOSES E. PIERSON, a citizen of the United States, residing at Emporium, in the county of Cameron and State of Pennsylvania, have invented a new and useful Incandescent-Lamp-Stem-Sealing Machine, of which the following is a specification.

This invention relates to a machine for sealing the filament-supporting stems in the bulbs of incandescent electric lamps, and relates more particularly to a machine of that type which burns off the surplus neck extension of the bulb, in addition to forming a seal between the filament-supporting stem and trimmed neck of the bulb, the machine requiring in its operation two attendants, one of whom looks after the trimming of the neck of the bulb and the positioning of the lamp parts in the revolving heads or holders, and the other looks after the sealing of the stems in the bulbs and the removal of the finished lamps from the heads.

The invention has for its principal object to improve and simplify the construction and operation of a machine of this character so as to be highly efficient in operation and readily manipulated, and in which the parts are so designed as to form a very compact structure in which the various instrumentalities are mounted on a common standard or column.

Another object of the invention is the employment of an improved means for rotating the lamp-carrying heads on their supporting spider or star only at points when the assembled lamp parts are opposite the preliminary and final heaters or burners, respectively.

Another object of the invention is the provision of novel means for supplying gas and air to the burner and blowers, respectively.

A further object is the provision of a novelly designed and arranged flame cut-off device in which the neck extensions of the lamps are trimmed preparatory to being assembled in the revolving rotary heads of the machine.

With these objects in view and others, as will appear as the description proceeds, the invention comprises the various novel features of construction and arrangement of parts which will be more fully described hereinafter and set forth with particularity in the claims appended hereto.

In the accompanying drawings, which illustrate one embodiment of the invention, Figure 1 is a perspective view of the machine. Fig. 2 is a plan view thereof. Fig. 3 is an enlarged vertical section of a portion of the machine, showing the manner of mounting the head-carrying frame, the means for driving the heads, and gas and air connections with certain of the burners. Fig. 4 is a perspective view of the pedestal and portions of the parts mounted thereon, showing the driving belt arrangement. Fig. 5 is a horizontal sectional view on line 5—5, Fig. 3. Fig. 6 is a detail sectional view on line 6—6, Fig. 3. Fig. 7 is a vertical section on line 7—7, Fig. 3. Fig. 8 is a vertical section of the rotary bulb-holding head of the neck trimming device taken on line 8—8, Fig. 2. Fig. 9 is a horizontal section on line 9—9, Fig. 8. Fig. 10 is a detail sectional view of the burner-supporting frame of the neck cut-off device. Fig. 11 is a detail sectional view of one of the burners.

Similar reference characters are employed to designate corresponding parts throughout the views.

Referring to the drawings, A designates the standard or supporting column of the machine on which the various parts thereof are mounted, and preferably the said column consists of a suitable length of pipe which has its lower end threaded in a base plate or disk 1 which is secured by bolts 2 or the like to the floor. On the upper end of the pipe standard is a cylindrical head 3, which, as shown in Fig. 3, has a tubular extension 4 that forms a pivot on which rotates the head-carrying frame or spider B. The head 3, together with its extension, may be considered as a part of the standard of the machine, as they are rigidly secured to the pipe section of the standard. At the root portion of the extension or pivot 4 is formed an annular shoulder 5 on which bears a ring 6 having its upper face inclined so that the ring constitutes a cam, which, by rotation, causes the head B to rise or fall for the purpose of positioning the lamp parts in the heads C in proper relation to the burners. Interposed between the hub 7 of the frame B and cam 6 is a collar 8 which is feathered on the extension or pivot 4 and which has its under side inclined to conform to the cam, so that as the cam is turned,

2
this collar will move up and down and hence raise or lower the frame B, the cam having a laterally-extending handle 9 whereby one of the attendants can manipulate the cam.

5 The frame B is a cruciform structure having, in the present instance, four radial arms 10 on the outer extremities of which are mounted the heads C which are capable 10 of rotating on their own axes and can be revolved around the standard A as a center. The hub 7 of the frame B has a central opening 11 through which the pivot extension 4 of the standard extends, and on the upper 15 end of said extension is fastened a collar 12 to retain the frame in place.

The lamp-carrying heads C are all of the same construction and each comprises a frame composed of top, bottom and intermediate cross members 13, 14 and 15, which are rigidly connected together by vertical rods 16 which pass through the ends of the said members. On the bottom member 14 is a centrally-disposed depending spindle 17 20 which extends through a bearing 18 in the outer end of a radial arm 10 of the frame B, as clearly shown in Fig. 3. The spindle 17 extends downwardly below the bearing 18 and is provided with a friction wheel 19 25 which is rigidly secured in place by a set screw 20, so that by means of the wheel, the lamp-carrying head can be rotated. The cross member 15 of each head is provided 30 with an opening 21 for receiving the neck or base portion of a lamp bulb b when in inverted position, and the upper member 13 has a larger opening 22 for receiving the enlarged portion of the bulb, as clearly 35 shown in Fig. 1. The filament-supporting stems s are supported on the upper ends of vertically-disposed rods 23 which form parts 40 of the heads, each rod passing vertically through and frictionally held in adjusted position in the spindle 17, as clearly shown 45 in Fig. 3, the lower ends of the rods being formed into knobs 24 whereby they can be conveniently gripped for adjustment. By moving these stem-supporting rods longitudinally, they can bring the flanged portion 50 of the filament-supporting stems in proper relation to the necks of the bulbs to provide for the proper formation of the seals.

The frame B is adapted to be rotated step by step to bring the lamps successively to 55 different working positions, and, for this purpose, the outer ends of the arms 10 are provided with handles 25 which one of the operators grips to turn the frame successively through ninety degrees.

60 A stop device is provided to hold the head-carrying frame in operative position with respect to the heaters, the said device consisting of a member or finger 26 secured to the cam-engaging collar 8, as shown in 65 Figs. 1 and 3, which finger has its upper end

provided with a socket 27 in which is seated a ball 28 that is adapted to enter a socket 29 in each arm as the latter are brought successively over the ball. When an arm 10 of the frame B moves into engagement with 70 the ball, the frame is raised on the central pivot or axis 4 by the ball acting as a cam, and as soon as the socket 29 is in line with the ball, the frame drops and will be held by its own weight in yielding engagement 75 with the stop device. To disengage the frame, the operator imparts a turning movement thereto, which will cause the frame to rise during the initial part of its turning by the cam action of the ball, and thus cause 80 the ball to be disengaged from the socket 29 of the arm. As soon as the arm passes off the ball, the frame will be supported by the hub 7 of the frame resting on the collar 8 until the next arm of the frame is brought 85 into engagement with the stop device.

The lamp-holding heads C are adapted to rotate only when they are opposite the preliminary heater H and the main or final heater H', so that the neck portion of the 9 bulbs will be heated uniformly. The heaters are arranged ninety degrees apart, and the stop device will arrest the frame B in such a position that a lamp will be opposite each heater. Therefore, separate driving 9 means must be employed for rotating those heads C which are supporting the lamps in co-operative relation with the heaters. For this purpose, friction driving wheels 30 are mounted at such points under the frame B 1 as to engage the friction driving wheels 19 of the lamp-carrying heads C. These wheels 30, which are provided with rubber or other yielding tires 30', are each mounted on a vertical shaft 31, Figs. 3 and 5, carried by the 1 bearing block 32 suitably supported on the standard of the machine at a point under the rotary frame B. On the lower end of each shaft 31 is a pulley 33 whereby the driving wheel is rotated. Each shaft is so mounted as to positively rotate the heads C as their wheels are brought into engagement with the driving wheels, despite the fact that the wheels 19 of the respective heads might be disposed at different radial distances from the axis on which the frame B turns, or that the wheels 19 are of different diameters. To thus compensate for these inaccuracies, the shaft 31 is mounted to rotate in a sleeve or bushing 34 disposed in the upper end of the bearing block 32, as shown in Fig. 3, and this sleeve is mounted on diametrically-disposed pivots 35 secured to the bearing block, so that the driving wheel can tilt laterally on the horizontal pivots as an axis. Mounted in the bearing block 32 is a spring-pressed follower 36 which bears against the sleeve 34 at a point below the pivots 35 and acts in such a manner as to throw the upper end of the shaft 31 and

hence the driving wheel 30 outwardly and into the path of the driven wheels 19 of the heads. This tilting movement under the tension of the spring-pressed follower 36 is limited by an adjustable stop 37 disposed diametrically opposite from the follower to engage the sleeve 34. When a driven wheel 19 is not engaged with either one of the driving wheels 30, the latter are inclined or tilted to the dotted line position, Fig. 3, and as soon as the wheels 19 are brought into engagement with the driving wheels by the operator turning the head B, the driving wheels will yield inwardly against the tension of the followers 36 until the wheels are frictionally engaged. The rubber tires or coverings of the driving wheels also compensate for slight inaccuracies and they co-operate with the spring-pressed followers to insure a firm engagement of the driving with the driven wheels. The means for rotating the driving wheels 30 is clearly shown in Fig. 4, and consists of a hollow rotary shaft 38 which is mounted to rotate on a fixed arm 39 fastened to the standard by a two-part collar 40 which is adjustably clamped to the standard, and on the shaft 38 is a pulley 41 driven from any suitable source of power by a belt 42. Also on the shaft 38 is a pulley 43 around which passes a belt 44 that extends upwardly to the pulleys 33 on the friction driving wheel shafts. The plane of rotation of the wheels 33 is horizontal, and hence at right angles to the plane of rotation of the pulley 43, and therefore the upwardly-extending flights of the belt 44 pass over idlers or guide pulleys 45 mounted on the bearing blocks 32, respectively. It will thus be seen that both friction wheels 30 will be driven by a common belt and rotate in the same direction.

The heaters are of the usual blast type and consist of gas jet nozzles 46 and blowers 47 which are so related to each other as to direct a plurality of flame blasts upon a common point to which the lamps are successively brought to be heated. The preliminary burner or heater and the outer section of the final burner or heater are supplied with gas and air, respectively, through pipes 48 and 49 which form supports for the nozzles and blowers. These pipes radiate from the enlarged portion or cylinder 3 of the standard from which they receive their supplies, and they also form supporting brackets for the bearing blocks 32 on which the latter are adjustable inwardly or outwardly on the said brackets to bring the friction driving wheels into proper relation with the driven wheels of the lamp-holding heads C. The pipes have their outer ends turned upwardly and are connected by a tie bar 50 so that the blowers will be held in fixed relation to the burner nozzles. As shown in Fig. 3, the cylinder 3 of the standard is divided

by a partition 51 into an upper gas chamber 52 and a lower air chamber 53, which latter communicates with the pipe section of the standard that has its lower end closed by a plug 54. These chambers are connected, respectively, by pipes 55 and 56 with a source of gas and an air pump and they serve as pressure equalizing devices so that the flames at the heaters will be more or less uniform and steady. The chamber 53 for the air is of substantial dimensions and is particularly useful in connection with a reciprocating air pump to prevent pulsations in the air pressure at the burners. The inner section of the main heater is supported by an arm 57, Figs. 1, 2 and 4, on the collar 12 at the upper end of the standard, and the gas and air are supplied from the chambers 52 and 53 through conduits 58 and 59 extending longitudinally of the pivotal extension 4 of the standard, there being hose connection between the upper ends of these passages with the burner nozzles and blowers. The supply of gas and air to the chambers 52 and 53 can be regulated by valves 60 and 61 in the pipes 55 and 56, and the different nozzles and blowers can be controlled by regulating valves 62, one of which is clearly shown in Fig. 11.

The device for cutting off or trimming the neck extensions of the bulbs is mounted, as shown in Fig. 1, on the standard A at a point adjacent the middle thereof and is supported on the outer end of a horizontal arm 63 secured to the standard by a clamping collar 64. The outer end of the arm 63 is provided with a bearing ring 65 which has its axis vertical to receive the stem or spindle 66 of a rotary head 67 in which the bulb is supported, the head being constructed somewhat after the fashion of the heads C to hold the bulb in inverted position, so that the flames from the heaters H² can be directed on the neck and cause the latter to melt off at the proper point. The lower end of the stem 66 is provided with a pulley 68 around which passes a belt 69, as shown in Fig. 4, which belt is driven from the shaft 38 that is provided with a pulley 70 around which the said belt passes. It will thus be seen that the bulb will rotate with the head 67, while the neck is disposed in the region of the flame blast. As shown in Fig. 9, the ball bearing 71 is provided between the bearing ring 65 and head 67 to insure free rotation of the latter. The ring 65 is cast or otherwise formed with oppositely-disposed horizontal arms 72 each of which has separate chambers 73 and 74 and are connected by hose or other conduits 75 and 76 with branches of the gas and air supply pipes 55 and 56, there being controlling valves 77 in said branches to regulate the supply of gas and air to the heaters H². The gas jet nozzles and blowers of

the heaters are screwed into or otherwise secured to the chambers 73 and 74 so as to receive gas and air therefrom.

The machine, as herein illustrated and described, requires two operators seated at opposite sides of the machine, the principal operator being adjacent the final heater to attend to the sealing of the lamps and the assistant adjacent the cut-off or trimming device. Assuming that the heaters are burning and that the belt and pulley transmission is operating, the assistant places a bulb to be trimmed in the continuously rotating holder 67 to cause the neck 15 of the bulb to be melted off. In this operation, the neck of the bulb closes and must be blown open by the assistant blowing a puff of air through the tubulature after removing the trimmed bulb and before it is 20 placed in that head C which is in front of her. Before the trimmed and blown bulb is placed in the head C, a filament-supporting stem is applied to the upper end of the rod 23 of such head, the bulb being slipped 25 downwardly over the filament until it comes to rest in the seats or openings 21 and 22 of the head. The carrier or frame B is then given a quarter turn to bring the head with the lamp part assembled therein opposite the preliminary heater where it remains during the time required for the 30 assistant to prepare and position the parts for the second lamp in the succeeding head. Thereafter the carrier or frame B is given another quarter turn to throw the first lamp 35 opposite the final heater and the second lamp opposite the preliminary heater, and at this point, the main operator gives her attention to the sealing of the first lamp. She notices the position of the assembled 40 parts of the first lamp with respect to the flame of the final heater, and if not in proper relative position, she turns the handle 9 of the cam 6 to raise or lower the carrier 45 or frame B, and hence the lamp with respect to the flame of the final heater which is stationary. The glass of the bulb and stem are thus melted and as soon as the 50 fusion of the parts is completed to form a seal, the lamp is removed from the heater by the principal operator turning the head-carrying frame B to thus bring the second lamp to the final heater and the third lamp, which has been assembled in the meantime 55 by the assistant operator, to the preliminary heater. The finished lamp is then removed by the principal operator who strengthens or draws out the filament-supporting stem if she finds it necessary, and in the empty 60 head she supplies a filament-supporting stem which is carried to the assistant as the empty head moves to a position in front of her. These operations go on in proper sequence very expeditiously so that a large 65 number of lamps can be turned out without

requiring any great or special skill on the part of the operators.

From the foregoing description, taken in connection with the accompanying drawings, the advantages of the construction 70 and of the method of operation will be readily apparent to those skilled in the art to which the invention appertains, and while I have described the principle of operation of the invention, together with the apparatus which I now consider to be the best embodiment thereof, I desire to have it understood that the apparatus shown is merely 75 illustrative, and that such changes may be made when desired as are within the scope 80 of the claims appended hereto, and many features of the present invention are well adapted for stem making machines.

Having thus described the invention, what I claim as new, and desire to secure by Letters Patent, is:—

1. In a machine of the class described, a supporting member, a rotatable carrier for lamps mounted thereon and provided on its under surface with a circular series of indentations, and a stop member on the support in the path of the indentations, the said carrier engaging the stop member by gravity and movable against the action of gravity to escape the stop member. 95

2. In a machine of the class described, a supporting member, a carrier rotatable on and movable along said supporting member, and a stop member for the carrier active to the latter by the gravitating movement of 100 the carrier, the latter moving against the action of gravity to escape the stop member.

3. In a machine of the class described, a suitable supporting member, a carrier for lamps rotatable on and movable along said 105 support, and a stop member beneath the rotatable carrier engaged by said carrier on its movement under the action of gravity and automatically releasing said carrier on a continuation of its rotative movement. 110

4. In a machine of the class described, a suitable support, a lamp carrier rotatable on and movable along said support and provided on the under side with a circular series of sockets, a bracket fast on the support and having a top surface provided with a socket, and a ball lodged in the socket in the bracket in the path of the sockets in the under surface of the carrier. 115

5. In a machine of the class described, a suitable support, a lamp carrier rotatable on and movable along said support and provided on the under surface with a circular series of rounded sockets, a socketed member on the support, and a ball lodged in said 120 socketed member in the path of the sockets on the under side of the carrier, the said sockets on the under side of the carrier being of less depth than the radius of the ball. 125

6. In a machine of the class described, a 130

pedestal, a rotatable carrier thereon, rotatable heads mounted on the carrier, a heater, means for arresting the carrier when the head is in co-operative relation with the heater, supply pipes for the heater constituting the sole support for the same and in turn carried by the pedestal, and a driving means for the rotatable heads on the carrier mounted on the supply pipes and provided with means for securing the driving means in position to be engaged by the rotatable heads when carried into operative relation to the heater.

7. In a machine of the class described, a pedestal, a rotatable carrier thereon, rotatable heads mounted on the carrier, a heater, supply pipes in spaced relation one to the other and extending from the pedestal to the heater for supporting the latter, a block traversed and carried by the pipes, driving means mounted on the block and means for securing the block to the pipes to hold the driving means in position to engage and drive a rotatable head when in operative relation with the heater.

8. In a machine of the class described, a pedestal, a rotatable carrier mounted thereon, a plurality of rotatable heads on the carrier, a plurality of heaters, supply pipes for the heaters secured to and extending from the pedestal and constituting the sole support for said heaters, the supply pipes being arranged in pairs with the pipes of each pair in spaced relation, blocks mounted on the pipes, driving means for the rotatable heads mounted on the blocks, means for securing the blocks to the supply pipes with the driving means in position to engage and rotate the heads when brought into coincidence therewith, and a common actuating means for the driving means carried by the blocks.

9. In a machine of the class described, a pedestal, a rotatable carrier mounted thereon, a plurality of rotatable heads on the carrier, a plurality of heaters, supply pipes for the heaters secured to and extending from the pedestal and carrying said heaters, the supply pipes being arranged in pairs with the pipes of each pair in spaced relation, blocks mounted on the pipes, means for securing the blocks to the pipes in any desired position therealong, driving means for the rotatable heads mounted on the blocks and positioned by the blocks to engage and rotate the heads when brought into coincidence therewith, a common actuating means for the driving means carried by the blocks, and a stop member for the rotatable carrier disengaged therefrom by a yielding movement of the carrier with relation to said stop member.

10. In a machine of the class described, a pedestal, a rotatable carrier mounted thereon, a plurality of rotatable heads on the

carrier, a plurality of heaters, supply pipes for the heaters secured to and extending from the pedestal and carrying said heaters, the supply pipes being arranged in pairs with the pipes of each pair in spaced relation, blocks mounted on the pipes, driving means for the rotatable heads mounted on the blocks and positioned to engage and rotate the heads when brought into coincidence therewith, a common actuating means for the driving means carried by the blocks, and a stop member for positioning the carrier with relation to the heaters, said rotatable carrier being movable in the direction of the length of the pedestal and yielding against the action of gravity to release from the stop member on the progressive movement of the carrier.

11. In a machine of the class described, a pedestal, a rotatable carrier mounted for rotation at the upper end thereof and capable of movement in the direction of the length of the pedestal, rotatable heads mounted on the carrier, heaters carried by the pedestal with supply pipes constituting the means of support for the heaters and in turn fast to and projecting from the pedestal, driving means for the rotatable heads mounted on the supply pipes in position to actuate the rotatable heads when in operative relation to respective heaters, impelling means for the head driving means common thereto, and a stop device on the pedestal active to the carrier by the gravitating movement of the latter.

12. In a machine of the class described, a pedestal, a rotatable carrier mounted for rotation at the upper end thereof and capable of movement in the direction of the length of the pedestal, rotatable heads mounted on the carrier, heaters mounted on the pedestal with supply pipes constituting the means of support for the heaters and in turn fast to and projecting from the pedestal, driving means for the rotatable heads mounted on the supply pipes in position to actuate the rotatable heads when in operative relation to respective heaters, impelling means for the head driving means common thereto, a stop device on the pedestal active to the carrier by the gravitating movement of the latter, and a manually operable cam member for moving the rotatable carrier along the pedestal in a direction contrary to the action of gravity thereon.

13. In a machine of the class described, a pedestal, a rotatable carrier mounted for rotation at the upper end thereof and capable of movement in the direction of the length of the pedestal, rotatable heads mounted on the pedestal with supply pipes constituting the means of support for the heaters and in turn fast to and projecting from the pedestal, driving means for the

- rotatable heads mounted on the supply pipes in position to actuate the rotatable heads when in operative relation to respective heaters, impelling means for the head driving means common thereto, and a stop device on the pedestal active to the carrier by the gravitating movement of the latter, the pedestal having a chambered interior with the individual chambers communicating with like pipes leading to the burners.
14. In a machine of the class described, the combination of a standard, a carrier rotatably mounted on the standard and adapted to move step by step, heads on the carrier, a heater, chambers in the standard, supply pipes extending from the chambers to the heater and forming a support for the latter, and a driving mechanism mounted on the supply pipes at a point below the carrier to successively rotate the heads.
15. In a machine of the class described, the combination of a supporting standard, a rotary carrier mounted thereon, rotary heads mounted on the carrier, a heater arranged adjacent the path of movement of the heads, supply pipes connected with the standard at a point under the carrier and extending laterally therefrom and connected with the heater, said supply pipes forming a support for the heater, a bearing block adjustably mounted on the supply pipes, a vertical shaft tiltably mounted on the bearing block, means for rotating the shaft, a device on the shaft for rotating the heads when the latter reach a point opposite the heater, and a yielding device for holding the said device in driving engagement with any head when it reaches the said position.
16. In a machine of the class described, the combination of a supporting standard, a carrier mounted for rotation thereon and adapted to move step by step, a plurality of rotary heads mounted on the standard, separate heaters arranged adjacent the path of movement of the heads and so positioned as to simultaneously align with separate heads, a supply chamber in the standard, separate pipes leading from the chamber to the respective heaters, and separate driving devices each mounted on a supply pipe and arranged to rotate those heads disposed in alignment with the heaters.
17. In a machine of the class described, the combination of a standard, a carrier mounted thereon for a rotary step by step movement, a plurality of heads rotatably mounted on the carrier at substantially the same radial distance from the center of the latter, a plurality of driving wheels mounted under the carrier and disposed at substantially the same radial distance from the axis of rotation of the carrier, driven wheels on the heads arranged to be engaged with the driving wheels, separate means for yieldingly holding the driving wheels in engagement with the driven wheels, means for holding the carrier stationary when the driving and driven wheels are engaged, and a common mechanism for rotating the driving wheels simultaneously.
18. In a machine of the class described, the combination of a standard, a carrier mounted thereon for a rotary step by step movement, a plurality of heads rotatably mounted on the carrier at substantially the same radial distance from the center of the latter, a plurality of driving wheels mounted under the carrier and disposed at substantially the same radial distance from the axis of rotation of the carrier, driven wheels on the heads arranged to be engaged with the driving wheels, separate means for yieldingly holding the driving wheels in engagement with the driven wheels, means for holding the carrier stationary when the driving and driven wheels are engaged, a common mechanism for rotating the driving wheels simultaneously, heaters disposed adjacent the path of movement of the heads, supports for the heaters, and means for supporting the driving wheels on the said supports.
19. In a machine of the class described, the combination of a standard, a head-carrying frame mounted on the standard, a plurality of heaters, separate chambers in the standard, gas and air supply pipes connected with the respective chambers, and pipes leading from the chambers to the heaters and forming supports for the latter.
20. In a machine of the class described, the combination of a standard, a head-carrying frame mounted on the standard, a plurality of heaters, separate chambers in the standard, gas and air supply pipes connected with the respective chambers, pipes leading from the chambers to the heaters and forming supports for the latter, an additional heater coöperating with one of the first-mentioned heaters, and means for conducting air and gas from the said chambers to the last-mentioned heater.
21. In a machine of the class described, the combination of a hollow standard, means for dividing the standard into separate chambers, a head-carrying frame mounted on the standard, heaters disposed in coöperative relation with the frame, pipes secured to the standards with their receiving ends communicating with the respective chambers and their outer ends connected with the heaters, an additional heater mounted on the upper end of the standard independently of the said pipes and coöperating with one of the first-mentioned heaters, and conduits in the standard communicating with the separate chambers thereof for supplying gas and air to the last-mentioned heater.
22. In a machine of the class described, a support, a rotatable carrier mounted there-

on for movement in the direction of the length of the support, and a stop device arranged to automatically engage the carrier for arresting movement thereof and automatically releasing the carrier to permit a resumption of its progressional movement by a movement of the carrier in a direction opposed to the action of gravity.

23. In a machine of the class described, a 10 rotatable carrier having a range of movement in opposition to the force of gravity, and a fixed stop member in operative relation to the carrier and acting to raise the carrier out of locking relation to the stop on the progressional movement of the carrier.

24. In a machine of the class described, a 20 standard constituting a pivot support, a carrier mounted to turn on the pivot support and to rise and fall thereon, said carrier having a series of spaced depressions on its under face concentric with the axis of rotation, a relatively fixed stop member on the standard in the path of the depressions to engage in the latter to arrest the 25 movement of the carrier and operating to raise the carrier on its progressional movement to release the said carrier from the stop member, and means for raising the carrier and stop member together.

30 25. In a machine of the class described, a rotatable carrier movable axially in opposite directions and constrained toward one limit of such movement by gravity, a stop member for the carrier acting thereon to 35 lift the carrier against the action of gravity to release said carrier on the progressional rotative movement of the latter, and means for raising the carrier and stop member together.

40 26. In a machine of the class described, a support forming a pivot, a rotatable carrier mounted thereon and movable therewith, said carrier being provided with spaced depressions in its under face, a 45 spherical stop member in the path of the depressions for engagement therein to hold the carrier against rotation, said stop member acting on the carrier to elevate the same on the progressional movement of the carrier and then upholding the carrier by engagement with its under face between the depressions, and means for raising the carrier and stop member together.

55 27. In a machine of the class described, the combination of a standard, a slidable collar mounted thereon, a carrier rotatably supported on the collar to turn about the standard as an axis, and a rotary cam on which the collar rests to raise and lower the 60 carrier.

28. In a machine of the class described, the combination of a vertically-disposed support, a carrier mounted to rotate on the support and to have a limited vertical movement, an annular cam rotatably mounted on

the support for raising and lowering the carrier, a plurality of heads on the carrier to rise and fall therewith, and a fixed heater mounted independently of the carrier.

29. In a machine of the class described, 70 the combination of a vertically-disposed support, a carrier mounted to rotate on the support and to have a limited vertical movement, an annular cam rotatably mounted on the support for raising and lowering the carrier, a plurality of heads on the carrier to rise and fall therewith, a fixed heater mounted independently of the carrier, and a device carried by the standard for stopping the carrier whenever the head thereon reaches a point opposite the heater. 80

30. In a machine of the class described, the combination of a supporting standard having a shoulder, an annular cam bearing on the shoulder, a collar bearing on the cam and adapted to slide longitudinally of the standard, and a rotary head-carrying frame supported on the collar and rotatable independently thereof on the standard. 85

31. In a machine of the class described, 90 the combination of a supporting standard having a shoulder, an annular cam bearing on the shoulder, a collar bearing on the cam and adapted to slide longitudinally of the standard, a rotary head-carrying frame supported on the collar and rotatable independently thereof on the standard, and a stop device mounted on the collar and arranged to arrest the movement of the carrier when the same reaches a predetermined 100 position.

32. In a machine of the class described, the combination of a standard, a rotary cam mounted thereon, a collar slidably mounted on the standard and resting on the cam, a 105 carrier slidably mounted on the standard and rotatably resting on the collar, a heater mounted in fixed position, a plurality of heads mounted on the carrier to move up and down therewith with respect to the 110 heater, a device carried by the collar, and spaced means on the carrier with which the device automatically engages to arrest the carrier when any head thereof reaches a point opposite the heater. 115

33. In a machine of the class described, the combination of a standard having a chamber and a pivot extension above the chamber, a carrier rotatably mounted on the extension, a plurality of heads on the carrier, a fixed heater having separate parts separately mounted on the standard, a pipe leading from the chamber to one part of the heater, a conduit in the pivot extension leading to the other part of the heater, and means on the pivot extension for vertically adjusting the carrier with respect to the heater. 120

34. In a machine of the class described, the combination of a standard having a 130

- chamber and a pivot extension above the chamber, a carrier rotatably mounted on the extension, a plurality of heads on the carrier, a fixed heater having separate parts 5 separately mounted on the standard, a pipe leading from the chamber to one part of the heater, a conduit in the pivot extension leading to the other part of the heater, means on the pivot extension for vertically adjusting the carrier with respect to the heater, and a device mounted on the pivot extension for arresting the movement of the carrier when any head thereof reaches a point in line with the heater.
- 15 35. In a machine of the class described, a supporting standard, a carrier rotatably mounted thereon, heads on said carrier, a heater having coöperating parts on opposite sides of the path of movement of the heads, 20 separate mountings for the coöperating parts of the heater carried by the standard, and fuel conduits leading to the standard and from there distributing to the separate heater parts.
- 25 36. In a machine of the class described, a chambered pedestal, a rotatable carrier mounted at the upper end of said pedestal, rotatable heads on said carrier, heaters having coacting parts on opposite sides of the 30 line of travel of the heads, supports extending from the pedestal to the heaters and constituting the conduits for fluid from the chambers in the pedestal to the heaters, and means carried by the pedestal for imparting 35 rotative movement to the rotatable heads when in operative relation to the heaters.
37. In a machine of the class described, a chambered pedestal, a rotatable carrier mounted at the upper end of said pedestal, 40 rotatable heads on said carrier, heaters having coacting parts on opposite sides of the line of travel of the heads, supports extending from the pedestal to the heaters and constituting the conduits for fluid from the 45 chambers in the pedestal to the heaters, means carried by the pedestal for imparting rotative movement to the rotatable heads when in operative relation to the heaters, and a stop member for positioning the rotatable heads with relation to the heaters, said 50 stop member becoming active to hold the rotatable carrier by the gravitating action of the latter.
38. In a machine of the class described, 55 the combination of a standard divided into separate chambers, a movable carrier on the standard, heads movably mounted on the carrier, a two-part heater arranged in coöperative relation with the heads, supply 60 conduits located exterior to the standard and connected therewith and with one part of the heater to form a support therefor, means for supporting the other part of the heater on the standard independently of the
- 65 said conduits, and conduits located in the standard for supplying the last-mentioned part of the heater with air and gas.
39. In a machine of the class described, the combination of a supporting standard having separate chambers for air and gas, means 70 for supplying the chambers, a rotary head-supporting carrier mounted on the standard at a point above the chambers, a two-part heater disposed in coöperative relation with the carrier, supply conduits connected with 75 the chambers and extending under the carrier and connected with one part of the heater, means above the carrier for supporting the other part of the heater on the standard, and means for supplying gas and air 80 to the last-mentioned heater.
40. In a machine of the class described, the combination of a supporting standard having separate chambers for air and gas, means for supplying the chambers, a rotary 85 head-supporting carrier mounted on the standard at a point above the chambers, a two-part heater disposed in coöperative relation with the carrier, supply conduits connected with the chambers and extending under the carrier and connected with one part 90 of the heater, means above the carrier for supporting the other part of the heater on the standard, means for supplying gas and air to the last-mentioned heater, and driving 95 means disposed under the carrier and mounted on the conduits for operating the heads of the carrier.
41. In a machine of the class described, the combination of a supporting standard 100 having separate chambers for air and gas, means for supplying the chambers, a rotary head-supporting carrier mounted on the standard at a point above the chambers, a two-part heater disposed in coöperative relation with the carrier, supply conduits connected with the chambers and extending under the carrier and connected with one part 105 of the heater, means above the carrier for supporting the other part of the heater on the standard, means for supplying gas and air to the last-mentioned heater, and means 110 for vertically adjusting the carrier with respect to the heater.
42. In a machine of the class described, 115 the combination of a supporting standard having separate chambers for air and gas, means for supplying the chambers, a rotary head-supporting carrier mounted on the standard at a point above the chambers, a two-part heater disposed in coöperative relation with the carrier, supply conduits connected with the chambers and extending under the carrier and connected with one part 120 of the heater, means above the carrier for supporting the other part of the heater on the standard, means for supplying gas and air to the last-mentioned heater, and a de- 125

vice mounted wholly on the standard at a point under the carrier for raising and lowering the same with respect to the heater.

43. In a machine of the class described, the combination of a supporting standard having separate chambers for air and gas, means for supplying the chambers, a rotary head-supporting carrier mounted on the standard at a point above the chambers, a two-part heater disposed in coöperative relation with the carrier, supply conduits connected with the chambers and extending under the carrier and extending with one part of the heater, means above the carrier for supporting the other part of the heater on the standard, means for supplying gas and air to the last-mentioned heater, a device mounted wholly on the standard at a point under the carrier for raising and lowering the same with respect to the heater, and a stop device for arresting the rotary movement of the carrier with any head thereof that is disposed in line with the heater.

44. A machine for sealing the filament-supporting stems to the bulbs of incandescent electric lamps comprising a single supporting standard or pedestal, a rotatable carrier mounted on said pedestal and provided with rotatable lamp supports, burners carried by the pedestal in operative relation to the rotatable carrier, another rotatable lamp support and burners in operative relation thereto carried by the standard or pedestal within reach of an operator placing the lamps on the rotatable carrier, and a common driving means for all the lamp carriers in turn supported by the pedestal, the means for carrying the last named support and burners therefor comprising a clamp collar adapted to the standard and an arm fast to the collar and supporting the rotatable head and burners.

tion thereto carried by the standard or pedestal within reach of an operator placing the lamps on the rotatable carrier, and a common driving means for all the lamp carriers in turn supported by the pedestal.

45. A machine for sealing the filament-supporting stems to the bulbs of incandescent electric lamps comprising a single supporting standard or pedestal, a rotatable carrier mounted on said pedestal and provided with rotatable lamp supports, burners carried by the pedestal in operative relation to the rotatable carrier, another rotatable lamp support and burners in operative relation thereto carried by the standard or pedestal within reach of an operator placing the lamps on the rotatable carrier, a common driving means for all the lamp carriers in turn supported by the pedestal, the means for carrying the last named support and burners therefor comprising a clamp collar adapted to the standard and an arm fast to the collar and supporting the rotatable head and burners.

In testimony, that I claim the foregoing as my own, I have hereto affixed my signature in the presence of two witnesses.

MOSES E. PIERSON.
